UNITED STATES PATENT OFFICE.

CHARLES J. LEHMAN, OF NEW YORK, N. Y.; PAULINE LEHMAN ADMINISTRATRIX OF SAID CHARLES J. LEHMAN, DECEASED.

LUBRICATOR FOR YARNS OR THREADS.

SPECIFICATION forming part of Letters Patent No. 752,458, dated February 16, 1904.

Application filed September 10, 1903. Serial No. 172,607. (No model.)

To all whom it may concern:

Be it known that I, CHARLES J. LEHMAN, a citizen of the United States, and a resident of the city of New York, borough of Manhattan, in the county and State of New York, have invented a new and Improved Lubricator for Yarn or Thread, of which the following is a full, clear, and exact description.

My invention relates to devices for lubricating yarn or thread of any character while it is present in winding machinery.

It is necessary to apply a lubricant to yarn or thread while it remains in winding machinery—as, for example, when it passes from a reel to a spool—and to accomplish this end I have devised a simple and compact device which is characterized by the employment of lubricant in a solid form as distinguished from a bath of liquid lubricant, whereby I am able to secure economy in the quantity of lubricant employed in the treatment of the threads, the latter being of any desired weight or color and of any suitable material, such as wool or cotton.

Further objects and advantages of the invention will appear in the subjoined description, and the actual scope thereof will be defined by the annexed claims.

Reference is to be had to the accompanying drawings, forming a part of this specification, in which similar characters of reference indicate corresponding parts in all the figures.

Figure 1 is a sectional elevation of a portion of one style of winding-machine, illustrating the application of my improved thread-lubricator thereto. Fig. 2 is an enlarged vertical cross-sectional elevation through the improved thread-lubricator, illustrating the course taken by a thread in passing through the device; and Fig. 3 is an elevation looking at the left-hand side of the thread-lubricator shown by Fig. 2.

To enable others to understand the invention, I have shown it applied to one style of machine by Fig. 1 of the drawings, wherein the numeral 5 indicates a spindle which passes upwardly through a table 6 and is adapted to carry a spool 7, on which is wound the thread, which may be of wool, cotton, or any other material. The thread from the skein is adapt-

ed to pass through a guide 8, which is mounted on a vertical rod 9, adapted to pass through a wooden frame 10 and through suitable guides 11, and to this rod 9 is pivotally connected a lever 12, which is fulcrumed on the hanger 13 and is adapted to be actuated by a cam 14 on a driving-shaft 15, whereby vertical reciprocating motion is adapted to be given to the rod 9 and the thread-guide 8. Suitable reels 16 are supported by arms or levers 17, attached to a post 18, and said reels 16 are disposed in the same vertical plane to receive a skein of yarn or thread, as represented in Fig. 1. The post 18 forms a part of the frame adapted to support a table 19, and on this table is mounted the thread-lubricator of my invention, said thread-lubricator being located between the spool 7 and the reels 16, which support the skein, whereby the thread as it passes from the reels to the spools is adapted to traverse the thread-lubricator in a way to be lubricated by the lubricant contained within said lubricating device.

The construction of my improved lubricating device is shown more particularly by Figs. 2 and 3 of the drawings, to which reference will now be made.

The leading feature of my invention is the provision of means by which lubricant of a solid nature may be applied advantageously to the thread of wool or cotton as it passes from the reels to the spool, and in the embodiment of the invention shown by the drawings the solid charge or mass of lubricant is indicated at A. Any suitable material may be employed, such as wax, which is arranged in lumps or balls and placed loosely within a receptacle 20. Provision is made for agitating the mass or charge of solid lubricant and for the passage of the thread B through such receptacle 20. As shown, the receptacle is adapted to be rotated on a horizontal axis, and to this end said receptacle is provided with diametrically-disposed hollow trunnions 21. The receptacle may be in the form of a drum having the oval cross-sectional contour shown by Fig. 2 and the circular shape shown by Fig. 3; but the particular form of the receptacle or drum is not material. The recep-

tacle is also provided with a charge-opening 22, adapted to be closed by a cover or door 23, which may be held in place by suitable means, and for the purpose of rotating the receptacle 5 or drum it is shown as being provided with a pulley 24, the latter being fast to or made in one piece with the drum on one side thereof and adjacent to one of the hollow trunnions 21. The drum is adapted to be mounted with 10 in a suitable frame, which is shown in the form of a yoke 25, said yoke having journal-bearings to receive the hollow trunnions 21. The drum is held in position within the yoke by any suitable means—such, for example, as 15 the cap-plates 26, which are fitted loosely to the upper sides of the hollow trunnions 21 and are fastened by screws 27 to the arms of the yoke 25. This yoke is provided at its under side with a depending boss 28, to which is attached 20 the upper extremity of a vertical stem 29, the latter being of any desired length. The stem is fitted in a socketed foot-piece 30, which is adapted to be fastened to the table 19 by any suitable means, and said stem is 25 clamped adjustably to the foot-piece by a binding-screw 31.

The yoke or frame 25 is provided with a laterally-extended arm 32, which carries a thread-guide 33 and a knot-catcher 34, said 30 guide and knot-catcher being of any suitable construction known to those skilled in the art.

The drum 20 is adapted to be rotated on the horizontal axis afforded by the trunnions 21 by the employment of an endless belt 35, 35 which is adapted to pass around the pulley 24 of said drum and to be driven by a pulley 36, which is made fast with the driving-shaft 15. At a point between the drum-pulley 24 and the driving-pulley 36 the belt 35 passes beneath 40 an idler-sheave 37, which is shown by Fig. 1 as being mounted below the table 19.

In the service of my device it is charged with a mass consisting of pieces, balls, or the like made from a suitable waxing or lubricating material, said charge or mass being introduced into the drum through the opening 22, after which the cover is readjusted. The thread B from the reels 16 passes through the knot-catcher 34 and the guide 33, thence 45 through the hollow trunnions 21 and chamber of the drum 20, and finally through the guide 8 to the spool 7, upon which it is wound. The winding-machine proper is operated in the well-known way, and the belt 35 drives the 50 drum 20, thereby agitating the mass or charge of lubricant A within the drum and causing it to fall or tumble around the thread. The thread is drawn from the reels onto the spool, and it is lubricated by the action of the mass 55 or charge A within the revoluble drum.

Although I have shown and described my

improvement in connection with a winding-machine of a given style, it will be understood that the lubricating device may be employed in connection with other styles of machines. 65 It is also evident that any desired number of these lubricating devices may be employed, and, as is common in winding machinery, the series of lubricating devices may be actuated or driven by a common belt, such as 35. 70

Having thus described my invention, I claim as new and desire to secure by Letters Patent—

1. A thread-lubricating device comprising a receptacle having means for the passage of a thread through the chamber thereof, said 75 receptacle being adapted to contain a charge of solid lubricant which is agitated around the thread by motion given to the receptacle, and means for imparting motion to the receptacle.

2. A thread-lubricating device having a receptacle provided with hollow trunnions and adapted to contain a charge of solid lubricant, and means for rotating said receptacle. 80

3. A thread-lubricating device having a receptacle adapted to contain solid lubricant in 85 the form of lumps or balls, means whereby a thread is conducted through the receptacle in position for access by the lubricant charge therein, and means whereby the lubricant charge may be agitated during the passage of 90 the thread through the receptacle.

4. A thread-lubricating device having a suitable frame, a receptacle provided with hollow trunnions and mounted in said frame for rotation therein, and means for rotating the receptacle on a horizontal axis. 95

5. A thread-lubricating device, consisting of a suitable frame, a drum provided with hollow trunnions and mounted in said frame for rotation on a horizontal axis, a pulley fast 100 with the drum, and a belt engaging with said pulley for rotating the drum.

6. A thread-lubricating device, consisting of a yoke-shaped frame, a lubricant-drum having hollow trunnions which are mounted in 105 said frame, cap-plates engaging with the trunnions and fastened to the frame, and means for rotating said drum.

7. A thread-lubricating device, comprising a yoke-shaped frame, a foot-piece, a stem attached to said frame and clamped to the foot-piece, a revoluble drum having means for the passage of a thread therethrough, and means for rotating said drum. 110

In testimony whereof I have signed my name 115 to this specification in the presence of two subscribing witnesses.

CHARLES J. LEHMAN.
